(57) **CLAIM**

The ornamental design for a display screen or portion thereof with a graphical user interface, as shown and described.

DESCRIPTION

The patent file contains a least one drawing executed in color. Copies of this patent with color drawing(s) will be provided by the Office upon request and payment of the necessary fee.

FIG. 1 is a front view of a display screen or portion thereof with a graphical user interface of the claimed design according to a first embodiment;

FIG. 2 is a front view of a display screen or portion thereof with a graphical user interface of the claimed design according to a second embodiment;

FIG. 3 is a front view of a display screen or portion thereof with a graphical user interface of the claimed design according to a third embodiment;

FIG. 4 is a front view of a display screen or portion thereof with a graphical user interface of the claimed design according to a fourth embodiment;

FIG. 5 is a front view of a display screen or portion thereof with a graphical user interface of the claimed design according to a fifth embodiment; and,

FIG. 6 is a front view of a display screen or portion thereof with a graphical user interface of the claimed design according to a sixth embodiment.

The dashed broken lines define the bounds of the claimed design and form no part thereof. The lightened toned perimeter rectangle showing the display screen or portion thereof forms no part of the claimed design. The lightened tone areas showing portions of the graphical user interface outside the dashed broken lines form no part of the claimed design. The white areas inside the dashed broken lines show portions of the display screen that form no part of the claimed design.

(Continued)

The lightened tone areas inside the dashed broken lines show portions of the graphical user interface that form no part of the claimed design.
